line 162 recited in the claims. It is the object of the present invention to provide a refrigerator assembly which is easily removable from the cabinet, and which may be easily replaced by unskilled mechanics.

UNITED STATES PATENT OFFICE

2,524,655

REFRIGERATOR ASSEMBLY

Robert M. Dunlap, Jackson, Mich., assignor to
The Sparks-Withington Company, Jackson,
Mich., a corporation of Ohio

Application November 15, 1946, Serial No. 710,012

1 Claim. (Cl. 62—116)

1

This invention relates to improvements in refrigerator assemblies and more particularly to the problem of the working parts within the assembly. For many reasons, it has become standard practice in the refrigerator industry to make a completely sealed assembly of all of the working parts of the refrigerator, especially including the compressor, evaporator, condenser and the lines associated with these parts. The cabinet is then built around this assembly in such a way that it becomes a major operation to attempt to replace some of the working parts of the refrigerator when they get out of order. It is also recognized that unskilled mechanics ruin many refrigerators in attempting to repair them after they have gotten out of order.

It is an object of this invention to provide a refrigerator cabinet from which the condenser, evaporator, compressor unit may be easily removed by unskilled labor, a new unit installed, and the original unit shipped to the factory for repair.

Another object is to provide a flat plate evaporator for installation in one wall of the refrigerator cabinet in such a manner that access may be had to this evaporator for replacement without removing the stored goods from the inside of the refrigerator and without requiring the complete dismantling of the cabinet.

Other objects and advantages of my invention will appear from the following description and drawings, in which

Fig. I is a top view of a table top refrigerator indicating the suggested arrangement of the parts embodying my invention.

Fig. II is a perspective view of the refrigerator, with the back plate and insulation removed, and the unit partially removed.

Fig. III is a vertical view of an evaporator plate indicating details of its construction and the lines from the compressor and condenser.

Fig. IV is a broken vertical sectional view on lines IV—IV of Fig. I.

Fig. V is a vertical view of the back of the refrigerator, showing a suggested arrangement of the parts.

Fig. VI is a sectional view, similar to Fig. IV but on a larger scale, indicating more of the construction of the evaporator plate, and

Fig. VII is a broken view in elevation showing a different type of flat plate evaporator which may be employed in such a refrigerator.

In the drawings the cabinet 10 is supported on base 12 and is equipped with any type of hinged closure or top opening lid 14, thereby enclosing

2

a suitable refrigeration compartment 16. The internal walls of compartment 16 are made of metal, and are described as inner liner 18. Between inner liner 18 and the outside wall of cabinet 10 is placed the customary insulation 20. Positioned below part of compartment 16 and beside part of compartment 16 is compartment 22, which houses the refrigerating mechanism, and is closed by screen or grille 24. The back wall 26 of cabinet 10 is constructed with an aperture 28 into which grille 24 is fitted, as well as aperture 30 which is closed by the removable plate 32, held in position by suitable means, such as screws 34. Positioned between compartment 22 and insulation 20, and internal from back wall 26 is channel or slot 36, the function of which will be more clear later.

The back plate evaporator 38 is shaped to fit one side of inner liner 18 and is held in position against inner liner 18 by means of screws 40; insulation 20 fills the space between evaporator 38 and back wall 26. Evaporator 38 is connected with condenser 42 by line 44, and to compressor 46 by line 48. Lines 44 and 48 are connected to evaporator 38 very close together and lines 44 and 48 run very close together and parallel from evaporator 38 down into compartment 16, through slot or aperture 36, thereby making it possible, as will be seen more fully later, to withdraw the condenser compressor evaporator unit from the cabinet 10 without removing lines 44 and 48. Line 50 connects the refrigerating mechanism by providing the means through which the refrigerant may be pumped into the system.

35 A very important feature of my invention is the selection of back plate evaporator 38, which is formed to give cooling over a large flat area and is also channeled so that inlet line 44 from condenser 42 may be placed very close to outlet line 48 into compressor 46. It is only by placing these two lines in close relationship where they enter evaporator 38 that full advantage may be taken of the removable feature through slot or aperture 36. There are any number of evaporators 38 available to do this job, and various types of evaporators will work. Evaporator 38 as shown in Fig. III or evaporator 38' as shown in Fig. VII are both channeled in such a way that inlet tube 44 may be positioned close to outlet tube 48 and still have the refrigerant reach all corners of the evaporator.

In order for the unskilled refrigerator mechanic to repair a refrigerator constructed according to my invention he would first remove screen or grille 24 and back plate 32, thereby exposing in-

sulation 20. Insulation may be in the form of batting or matting or it may be the loose type of insulation; in either case insulation 20 is removed, thereby exposing evaporator 38. Screws 40 which hold evaporator 38 in close contact with inner liner 18 are next removed, along with any stabilizing attachment found necessary to hold the condenser 42 and compressor 46 in compartment 18. At this point it will be found that there is enough flexibility in lines 44 and 48 to allow evaporator 38 to be maneuvered out of cabinet 10 through aperture 30 in back wall 26, and at the same time to remove condenser 42 and compressor 46 out through aperture 28, having lines 44 and 48 follow out through slot 36. The entire unit may be slid out of the cabinet and into a specially designed shipping crate in which it may be shipped to the central factory for repair. A substitute unit may be installed in cabinet 10 by reversing the removing process thus described.

Having thus described my invention what I claim as new and desire to protect by Letters Patent is:

A refrigerator assembly comprising a cabinet 25 having outer insulating walls, a refrigeration compartment enclosed by said cabinet, an inner liner defining said compartment, a refrigerating

unit, a second compartment adapted to house said refrigerating unit and positioned adjacent said first compartment, a flat plate evaporator in heat exchange relation with said inner liner, refrigerant lines connecting said flat plate evaporator with said refrigerating unit and positioned close together at the point of connection with said evaporator for at least a substantial part of the length between said evaporator and said refrigerating unit, a wall structure between said compartments having a slot defined therein and through which said lines extend, and apertures defined in one of said outer walls into which said slot opens to enable said evaporator, lines, and 10 refrigerating unit to be removed thereto from said cabinet without disconnecting said lines.
